ROLL SCREEN INSTALLING DEVICE

Minas Yartyan, New York, N. Y.

Application March 5, 1935, Serial No. 9,498

4 Claims. (Cl. 156—39)

This invention relates to a device for installing a ventilating screen of the roll type in conjunction with window frames and analogous structures providing light and ventilation.

The principal object of the invention is the provision of a novel device with which a screen of the indicated character may be readily installed and removed; which retains the screen material taut and smooth spanning the window opening; which makes it possible to wind the screen material so as to be clear of a desired portion of the window opening whenever it is necessary or desirable.

The invention consists in the novel arrangement and combination of the various parts, as well as the details of construction.

The nature of the invention and its distinguishing features and advantages will appear when the following specification is read in connection with the accompanying drawings, in which:

Fig. 1 is an inside view of a device embodying the features of an invention, the screen being arranged in a window frame, and portions of the screen and frame being broken away;

Fig. 2 is an enlarged section taken on the line 2—2 of Fig. 1;

Fig. 3 is a section taken on the line 3—3 of Fig. 2;

Fig. 4 is a perspective view of one of the bracket bearings detached;

Fig. 5 is a fragmentary perspective of one section of the screen roller housing or casing;

Fig. 6 is a fragmentary perspective of the other section of the housing or casing;

Fig. 7 is a fragmentary view of one of the connecting guide rods;

Fig. 8 is an enlarged detail sectional view showing certain features; and

Fig. 9 is a section taken on the line 9—9 of Fig. 8.

Referring now more particularly to the several views of the drawings, it will be apparent that the device of the present invention includes a supporting and guiding structure adapted to be arranged in a window frame, and which supports and encloses a spring roller for the screen material, and which guides the screen material as it is wound on and unwound from the roller. The said structure includes a base or sill bar 10, connecting guide tubes 11, and a housing or casing 12 within which the roller for the screen material is arranged. Each of the tubes 11 is of hollow construction and has a slot 13 extending longitudinally thereof and which terminates short of the lower end, and which is widened and opens

through the upper end as at 14 for a purpose to appear. The tubes 11 are disposed vertically in spaced parallel relation between the bar 10 and the housing 12. The lower end of each of the tubes 11 is connected with the bar 10 by an adjusting screw 15 which is swivelly connected with the bar 10 as at 16. The screw 15 has a plurality of radially disposed holes 17 therein to receive a suitable instrument for the purpose of turning the screw 15 to adjust the tube 11 up and down. A bracket bearing 18, shown most clearly in Fig. 4, is mounted on the upper end of each of the tubes 11. To accomplish this, the bearing 18 has a depending portion 19 which fits into the tube, the latter having a notch 20 to receive a laterally extending pin 21 on the portion 19 to prevent the bearing 18 from turning with respect to the tube. The portion 19 has a groove 22 therein complementary to the slot 13 in the tube. It will be obvious that each of the bearings 18 is detachably connected with the upper end of the related tube 11. The housing 12 is removably supported by the bearings 18. The housing 12 is constructed preferably of heavy sheet metal and comprises two sections, a section 23 and a section 24. Each end of the housing section 23 has a depression or recess 25, and a slot 26. Each end of the housing section 24 has an integral portion 27 whose upper end has a flange 28. Due to the resiliency of the metal the portions 27 serve as springs. The portions 27 are receivable and fit within the depressions 25 respectively, and the flanges 28 are engageable and fit in the slots 26 respectively in the housing section 23. Thus the housing section 24 may be detachably associated with or secured to the housing section 23. The housing section 24 is narrower than the section 23 to close a portion of the bottom of the section 23 and also to leave an opening extending longitudinally of the housing at the back thereof through which the screen material is wound and unwound. The housing section 24 has a longitudinal reinforcing flange 29 which abuts the front wall of the housing section 23. If desired each of the bearings 18 may be provided with a depending bracket 30 for the purpose of supporting the roller of an ordinary window shade. In order to accommodate the bracket on each of the bearings 18, the housing section 24 has an opening 31 therein. The housing 12 is mounted on or supported by the bearings 18 which are disposed within the same.

The bearings 18 constitute means for supporting a spring and ratchet roller 32 of any suitable construction including trunnions which are re-

ceived in holes 33 in the bearings 18 respectively. A piece of screen material 34 of suitable size to span the distance between the tubes 11 and to reach from the roller 32 to the bar 10 is provided.

5 The upper end of the material 34 is secured to the roller 32 in any practical manner, and the opposite side edges of the material 34 extend or project into the slots 13 of the rods 11 respectively, as the material 34 is wound on and unwound from the roller 32, the walls of said slots 13 constituting guiding means for the material. The lower end of the material 34 is bent in connection with a longitudinally bent strip 35 having a forwardly projecting flange 36 throughout the length thereof. Another strip 37 approximately equal in length to the strip 35 is laid against the bent end of the material 34. Suitable fastening elements 38 are employed to fasten the strips 35 and 37 together in binding engagement with the material 34. Each of the strips 35 and 37 at the opposite ends thereof is notched as at 39 to clear the unslotted lower end portion of the tube 11, so that the flange 36 may be brought down into contact with the bar 10. Suitable latches 40 are secured to the strip 37. Each of the latches has spring pressed latch members 41 which are releasably engageable with a headed stud 42 secured to the bar 10. The flange 36 has openings 43 therein to accommodate the studs 42. A suitable handle 44 is secured to the strip 37 intermediate the ends thereof for the purpose of winding and unwinding the material 34. The latches 40 will automatically engage the studs 42 when the material 34 is unwound sufficiently so that the material 34 will entirely close the opening of the window frame 45. The latches 40 must be manually released to wind the material 34 on the roller 32. It will be understood that the reaction of the spring of the roller 32 will cause the material 34 to wind on the roller, subject to the action of the ratchet of the roller which will retain the material 34 extended in such manner as to be clear of any desired portion of the window opening whenever it is necessary or desirable.

45 The various elements will be so proportioned as to apply the screen to a window frame of known size. The screen will be retained in place by means of the screws 15 which exert upward and downward pressure causing the bar 10 to bear on the sill of the frame 45 and the housing 12 to bear against the head rail of the frame 45 with sufficient force to hold the screen in place.

50 By widening the slots 13 at the upper ends, as indicated at 14, the material 34 will always be

caused to enter the slots 13 if for any reason the opposite side edges should leave the slots.

I claim:

1. A supporting and guiding device including bearings, vertical spaced parallel guides, a base 5 bar, means adjustably connecting the lower ends of the guides with said bar, said bearings being detachably connected with the upper ends of said guides respectively, said bearings being designed to support a spring roller, so that suitable material may be wound on and unwound from the roller with the opposite side edges of said material disposed for guided movement by said guides respectively.

2. A supporting and guiding device including 15 bearings, vertical spaced parallel hollow longitudinally slotted guides, a base bar, means adjustably connecting the lower ends of the guides with said bar, said bearings being detachably connected with the upper ends of said guides respectively, said bearings being designed to support a spring roller, so that suitable material may be wound on and unwound from the roller with the opposite side edges of said material movable in the slots in said guides to be guided by the walls 25 thereof respectively.

3. A supporting and guiding device including a base bar, vertical spaced parallel guides rising from the bar, bearings on the upper ends of said guides respectively, said bearings being designed 30 to support a spring roller, so that suitable material may be wound on and unwound from said roller with the opposite side edges of said material disposed for guided movement by said guides respectively, and means to releasably fasten the 35 lower end of the material to the bar.

4. For arrangement in a window frame, a device comprising bearings, vertical spaced parallel tubes each having a longitudinally extending slot opening through its upper end, said bearings being detachably connected with the upper ends of said tubes respectively by means on the bearing projecting into said tubes, a sill bar, and means adjustably connecting the lower ends of said tubes with said bar, said bearings being designed to 45 detachably support a housing and a spring roller within said housing horizontally disposed, so that screen material may be wound on and unwound from the roller through an opening in said housing with the opposite side edges of the screen 50 material guided by the walls of the slots in the tubes respectively.

MINAS YARTYAN.
